UNITED STATES PATENT OFFICE.

NIELS C. NIELSEN, OF CLEVELAND, OHIO.

FOLDING TABLE.

1,103,532.

Specification of Letters Patent. Patented July 14, 1914.

Application filed December 19, 1913. Serial No. 807,682.

To all whom it may concern:

Be it known that I, NIELS C. NIELSEN, a subject of the Kingdom of Denmark, residing at Cleveland, in the county of Cuyahoga and State of Ohio, have invented certain new and useful Improvements in Folding Tables, of which the following is a specification.

This invention relates to folding tables, 10 and particularly to portable folding tables especially adapted for the use of paper hangers and the like.

The object of the invention is to provide an improved metal cutting strip and attachments for use in connection with such a folding table.

The invention is illustrated in the accompanying drawings in which—

Figure 1 is a perspective view of the table. 20 Fig. 2 is a bottom plan view of the table with the legs folded. Fig. 3 is a perspective view showing the table folded up for transportation. Fig. 4 is a detail in perspective of the cutting strip. Fig. 5 is a detail in 25 section of a device for tightening the cutting strip and holding the same on the table.

Referring specifically to the drawings, 6, 30 6^a, and 6^b are sections of the table top, the end section 6 being hinged to the middle section 6^a by hinges 7 at the ends, so that these two sections will fold one against the other. The opposite end of the middle section 6^a is hinged to the other end section 6^b by hinges 7^a secured to depending cross 35 pieces 7^b at the adjacent ends of the sections, these cross pieces being sufficiently wide to form a space between the sections 6^a and 6^b in which the end section 6 fits when the table is folded, as shown in Fig. 3.

40 Each section of the table has pairs of crossed folding legs 8 the side pieces of which are pivoted together at 20, and one set of legs of each section has a cross piece 21 at the upper end which will engage against a cleat 10 fastened to the underside of the 45 top leaf or section, the face of the cleat being recessed to receive the cross bar 21 and hold the legs in set up position. When the legs are folded, the cross bar 21 is with-

drawn from the cleat and then the legs are 50 folded flatly against the underside of each leaf, as shown in Fig. 2. With the legs in this position, the section 6 can then be folded over against the section 6^a and the section 6^b over upon the section 6, thereby forming 55 a compact structure as indicated in Fig. 3, the sections being fastened together in such folded position by means of a pivoted catch 17 at one edge. In this folded position, the table can be readily transported or carried 60 in the hand, a handle 18 being provided for the purpose.

A flexible metal cutting strip 13 is provided and can be fixed along one edge of the table when it is set up. This strip has at 65 one end a hook 14^a which will engage under the rim or flange at the end of the table, and the strip extends thence along the edge of the top of the table to the opposite end where it is fixed and tightened by means of a device 70 shown in Fig. 5, comprising a folded sheet metal member 14 which may be hooked under the flange at that end.

The end of the strip 13 is attached to the fold 14^b of the member, after being bent 75 over the corner or end, by means of a thumb screw 19, and then the strip is tightened by a thumb screw 16 which is threaded through the outer fold 14^b of the attaching device and bears at its inner end against the body of 80 said device, whereby the part 14^b can be sprung out or away from the end of the table thereby exerting tension on the strip 13 and tightening the same. The strip 13 is held to close contact with the table top by means of 85 ears 12 which fit through slots 11 in the table top and are fastened underneath by pins 15 inserted in holes 12^a in the ears. By removing the pins and loosening the attaching devices at the ends of the strip, the latter can be detached and rolled up and if desired placed inside the box or casing formed by the folded table illustrated in Fig. 3, or otherwise carried conveniently.

The folding legs 8 are so constructed that 90 one member or pair thereof nests or fits within the other member when they are folded to parallelism, as shown in Fig. 2.

What I claim as new is:

The combination with a table top, of a flexible cutting strip adapted to be placed thereon, means to attach one end of the strip to the table, and a straining and holding device for the strip at the other end thereof, said device having a spring part to which the end of the strip may be attached, and a

screw operating on said part to draw the strip taut.

In testimony whereof, I do affix my signature in presence of two witnesses.

NIELS C. NIELSEN.
